UNITED STATES PATENT OFFICE.

FRANK W. EVELAND, OF HOT SPRINGS, ARKANSAS.

LIQUID-FUEL BURNER.

1,099,542.

Specification of Letters Patent.

Patented June 9, 1914.

Application filed May 24, 1913. Serial No. 769,706.

To all whom it may concern:

Be it known that I, FRANK W. EVELAND, a citizen of the United States, residing at Hot Springs, in the county of Garland and 5 State of Arkansas, have invented certain new and useful Improvements in Liquid-Fuel Burners, of which the following is a specification.

My invention relates to burners which 10 utilize liquid fuel as the heating medium and which liquid fuel is volatilized or converted into a gas by passage through a retort in a heated state prior to ignition.

The main object of my invention is to provide a construction wherein substantially 15 complete combustion will take place to the end that but a very inappreciable carbon or soot deposit will take place in the retort and burner, avoiding the necessity of frequent 20 cleaning of the parts.

In carrying out the said objects, important 25 objects are to construct a device of this character that will be highly effective in operation, durable in use, simple in construction and capable of manufacture at minimum cost.

Another important object of the invention 30 is to provide a regulating means for the supply of air to the burner employed.

With the foregoing and additional objects 35 in view, such as will appear hereinafter from the following description taken in connection with the accompanying drawings, one approved form of the invention is disclosed.

In said drawings: Figure 1 is a side view 40 in elevation of the burner; Fig. 2 is a top or plan view of the starting pan of the burner; Fig. 3 is a longitudinal sectional view through the said starting pan, showing fragmentarily in connection therewith, the 45 burner; and Fig. 4 is a detail vertical sectional view through the retort coil.

Referring specifically to the drawings, the main supply pipe connects to the burner 50 structure at the coupling or joint 1. From this joint 1 rises an upstanding conduit pipe 2 connected to a valve 3, in turn connected to a substantially horizontally disposed intake or crown portion 4 of a retort 5 formed of a plurality of hollow helical coils 5'. The valve 3 is operable to control the supply of fuel from the supply pipe through the crown pipe 4. The retort coils define between them a space centrally of which is connected to 55 the lowermost coil an elbow 6 which is in turn connected to an elongated burner pipe

7, which body extends on opposite sides of the elbow 6, diametrically of the coils. On each of opposite sides of the elbow 6, burner pipe 7 is provided with an outlet orifice 8 60 for fuel.

A starting pan designated 9 is employed and this pan has end walls 10 rising therefrom, provided with notches 11 in which the burner pipe 7 rests. Also the starting pan is provided with openings 12, one below each burner orifice 8, said openings being surrounded by frusto-conical hoods 12', the latter having notches 13 at their top in which the burner pipe 7 also rests. In each hood 65 is mounted a damper 13', each of which is preferably constructed of cast iron, and which are connected to a rod 14 turnably mounted in the hood and being provided with a handle at 15 to facilitate adjustment 70 of the dampers. Suspended from the crown pipe portion 4, by means of two bolts 6' are circular deflector plates 8' which are fastened to the bolts by means of nuts 7'. An auxiliary nether fuel supply pipe 16 is employed and leads from the coupling 1, having connected thereto a valve 17 to control 75 the supply of fuel therethrough.

In the operation of the burner, with the valve 3 closed, valve 17 is opened whereupon a proper amount of liquid fuel flows into the starting pan. Thereupon said valve 17 is closed and the fuel is ignited, the flame produced effectively heating the retort 5. When the retort 5 has been sufficiently heated to convert liquid fuel to a gas, valve 3 is opened, and liquid fuel then passes from the supply pipe through the coupling 1, through pipe 2, valve 3, crown portion of pipe 4 and through the coil 5, being vaporized while in 80 the coil 5, and issuing from the coil through the coupling 6 into the burner pipe 7 and out of the orifices 8. At this stage the flame from the pan 9 persists and ignites the fuel issuing from the orifices, the flames from the 85 said orifices rising in the space defined by the retort and effectively heating the retort so that as the fuel is supplied, it will be effectively vaporized or volatilized before issuance through the orifices 8. Dampers 13 90 are operable to control the amount of air admitted to the burner.

It is to be understood that merely the preferred embodiment of the invention has been illustrated and described and that changes 95 may be made within the spirit and scope thereof.

Having thus described my invention what I claim is:—

1. In a device of the character described, a supporting structure provided with an up-standing hood surrounding an air-intake opening, said hood having notches at its top, a burner member seated in said notches, said member having a burner orifice adjacent the top of and within the limit of the hood, 10 and a continuous coil forming a retort section over the hood and located above and in communication with said burner member and arranged to be heated by the flame issuing from the burner orifice.
- 15 2. In a device of the character described, a supporting structure provided with an up-standing hood surrounding an air-intake opening, said hood being frusto-conical in shape, a burner member mounted adjacent 20 the top of said hood having a burner orifice adjacent the top of and within the limit of the hood, a damper within the hood, means for operating and supporting the damper rotatably mounted in the hood, and a retort section above and in communication with

said burner member and arranged to be heated by the flame issuing from the burner orifice.

3. In a device of the character described, a supporting structure provided with an up-standing hood frusto-conical in shape and surrounding an air-intake opening, said hood having notches, a burner member seated in said notches, said member having a burner orifice adjacent the top of and within the 35 limit of the hood, a damper within the hood, a rod supporting the damper turnably mounted in said hood, and a continuous coil forming a retort section over the hood, located above and in communication with 40 said burner member, and arranged to be heated by the flame issuing from the burner orifice.

In testimony whereof I affix my signature in presence of two witnesses.

FRANK W. EVELAND.
